COATRACK FOR ATTACHING TO A STOOL

Ralph Pepper, 230—31 57th Road,
Bayside, N.Y. 11364

Filed Mar. 10, 1972, Ser. No. 233,869

Term of patent 14 years

Int. Cl. D6—06
U.S. Cl. D6—116

FIG. 1

FIG. 2

FIG. 3

FIG. 4

FIG. 5

FIG. 6

FIG. 7

FIG. 8

FIG. 9

FIG. 10

FIG. 1 is a side elevational view of the preferred embodiment of a coatrack for attaching to a stool;

FIG. 2 is a rear elevational view thereof;

FIG. 3 is a front elevational view thereof;

FIG. 4 is a top plan view thereof;

FIG. 5 is a bottom elevational view thereof;

FIG. 6 is a side elevational view of an alternate embodiment of a coatrack for attaching to a stool;

FIG. 7 is a rear elevational view thereof;

FIG. 8 is a front elevational view thereof;

FIG. 9 is a top plan view thereof; and

FIG. 10 is a rear elevational view thereof.

I claim:

The ornamental design for a coatrack for attaching to a stool, as shown and described.
